UNITED STATES PATENT OFFICE

2,600,240

CONSTRUCTION OF INCUBATORS FOR
INFANTS

Benjamin Curtis Grieb, Chestnut Hill, Pa., assignor, by mesne assignments, to Children's Hospital of Philadelphia, Philadelphia, Pa., a corporation of Pennsylvania

Application May 22, 1948, Serial No. 23,603

12 Claims. (Cl. 128—1)

1

This invention relates to incubator apparatus suitable for use for infants such as those which are prematurely born or those requiring special care and isolation. The invention is particularly concerned with improvements in the construction of such apparatus which increases the effectiveness of the protection provided by such devices.

Apparatus of this nature which incorporates all of the equipment and controls desirable for providing effective isolation, adequate temperature and humidity control, proper handling equipment and the like, has heretofore been extremely complicated, expensive to manufacture and awkward to handle. Consequently such equipment has usually provided only the more urgent safeguards.

It is the primary object of the present invention to provide an incubator construction which is capable of being used in a number of different ways and which permits even the most rigorous isolation.

In order to provide an incubator construction which is compact and easily handled while at the same time includes all the equipment needed to give complete control of the air supplied and means to allow full isolation, the present invention provides for an incubator assembly having two main components. In one of these components the mechanical and electrical equipment for circulating and conditioning the air or gas for the incubator is located. The other component is the occupant's chamber which is chiefly structural in nature. By separating the apparatus from the isolation space the manufacture and assembly are greatly simplified.

In the present invention it is an object to provide a relatively shallow base unit arranged to contain the various operating and control mechanisms in a compact and orderly arrangement which allows step-by-step assembly and installation operations. Such construction also obviously simplifies service and repair work.

An important object of the invention is to provide complete indicating and warning apparatus for indicating proper functioning of the circulating system and operation of the heating device. Means to provide adequate warning of malfunctioning of the equipment are incorporated.

When using incubators of this type it is often desirable to administer oxygen in various concentrations. It is an object of the present invention to provide improved means for this purpose including a mixing and distributing system which produces an even distribution of the desired oxygen concentration throughout the en-

2

closure. Medicaments or the like may also be added to the air supply in a manner similar to the addition of oxygen.

Apparatus of this nature may be used under many different circumstances. For example, an isolation unit of the present type may be located in a hospital room so that a new infant may be kept with its mother while being protected from any undesirable contact. The more usual method 5 of using is for a number of incubator units to be kept together in a nursery under the care of an attendant. In some instances it may be desirable to supply an incubator for each infant with the object of preventing epidemics. Under various 10 conditions of use it is desirable that the occupant of the incubator be readily observed from any angle. For this purpose the present invention provides an unusually clear view of the interior of the occupant's space because of the 15 manufacture of the upper portion of the unit from transparent material.

Usually the patient is left in the incubator for extended periods when isolation is desired. Since 20 complete care may be administered while the infant remains inside the enclosure there is no need for removing and thus causing exposure to air-borne infection or change in environment. The present construction which permits insertion from the bottom of the enclosure has certain advantages in addition to simplified structure. In 25 previous constructions having a lid at the top, opening of the lid for insertion of a patient permitted the loss of a considerable amount of heated air from the incubator. With the present 30 construction the heated and conditioned air is entrapped in the enclosure during opening so that little time is required to return the inside air to the desired condition after insertion of a patient.

A further object of the invention is the provision 35 of apparatus which allows improved control over the humidity both during the circulation of air while the heater is in use or when no heat is being applied.

It is realized that the present apparatus includes 40 general features disclosed in prior patents, for example, Patent 2,243,999, issued June 3, 1941, to Charles C. Chapple. The detail features herein disclosed are directed toward improvements which are intended to simplify construction, reduce cost, increase safety and provide 45 an incubator of increased versatility and usefulness.

The manner in which the foregoing and other objects and advantages associated with the present 50 invention are accomplished will be clear from

the following description of the drawings, in which—

Figure 1 is a perspective view of an incubator incorporating the present invention.

Figure 2 is an end elevational view of the apparatus illustrated in Fig. 1 with the enclosure in open position.

Figure 3 is a plan view of the base unit of the present apparatus having the lid removed to show the interior arrangement.

Figure 4 is a front elevation of the apparatus illustrated in Fig. 3, the front face of the box being removed for purposes of disclosing the interior arrangement.

Figure 5 is a sectional view taken in the direction of arrows 5—5 of Fig. 3.

Figure 6 is a sectional view through the access door.

Figure 7 is a sectional view through one of the portholes showing the manner of attachment of the sleeves.

Referring to Figs. 1 and 2 it will be seen that the incubator unit consists primarily of the transparent box or dome 10 and the lower base unit 11. The enclosure dome 10 is hinged along one edge by a piano type hinge 12 to permit opening in the fashion clearly illustrated in Fig. 2. Opening in this manner allows access directly at the mattress level and simplifies the operation of placing an infant in or removing it from the incubator. Links 13 are pivotally connected to the dome 10 and the base 11 in the fashion illustrated to provide for retention of the cover unit in the open position.

In order to separate the base chamber from the occupant's space a lid plate 14 which is most clearly illustrated in Figs. 1 and 4 is provided. The lid 14 is supported on angle members 15 around the upper edge of the base box 11. The lid 14 forms the floor of the occupant's space. A low sheet metal wall 16 is attached to the floor 14 in a fashion to provide for proper positioning of a suitable mattress 17. A separate plate or tray 18 is located to fit underneath the mattress 17. Plate 18 incorporates a turned-down flange 19 which may be used to retain the tray 18 in a slightly inclined position when the lip 19 is placed over the edge of the wall 16 as illustrated in Fig. 4. This arrangement permits either a flat or inclined position for the mattress 17, thus providing for increased comfort of the occupant by permitting a change of position. In some instances it may be desirable from a medical standpoint to use the inclined position for either raising or lowering the head of the infant in relation to its body. The angle 20 attached to the lid 14 positions the tray 18 and the mattress 17 in endwise direction.

The hinge 12 which connects the enclosure 10 to the base unit 11, being of the piano type is readily disconnected by removal of the hinge wire which is preferably made in two pieces for ease in removal of the enclosure 10 from the base 11. A tight joint to prevent the escape of air around the bottom of the enclosure is assured by the soft gasket 15a on which the enclosure rests. Rapid separation of the enclosure from the base is of considerable advantage both during manufacture of the incubator and during servicing or cleaning of the various parts.

While the apparatus of the present invention may provide for the complete conditioning of the air or gas supply to the occupant it will be seen that all of the apparatus and controls required for this purpose are completely housed in

the base unit 11. Reference to Figs. 3, 4 and 5 will disclose the details of the conditioning and circulating apparatus. The electrical equipment is contained chiefly in the chamber 21. Chamber 21 is entirely separated from the interior of the base box 11 by means of the walls of the box 21 and its lid which is securely fastened on by screws 22, there being incorporated a suitable sealing gasket. The lid is thus readily removable for purposes of inspection and repair. Enclosed within the box 21 are the fan motor 23, the transformer 24 and such other electrical equipment as the operating relays, alarm buzzer, etc. The electrical lead wire 25 is used to supply the current for operating the incubator. Oil cup 26 supplies the lubrication for the motor. Provision is made for the circulation of air from outside the unit through the back wall and bottom of the base 11 to the electrical box 21 in order to give adequate ventilation for the electrical compartment, as by louvers 21a.

Blower fan 27 is driven by the motor 23 and provides for the circulation of air or gas in the incubator. A tube 28 leads to the center of the blower unit 27 and provides the intake for the blower. Thus, the recirculated air from the unit is sucked in through tube 28 into the blower and forced through the unit. New air is supplied by means of a connecting fitting 29 to which a hose 30 may be attached leading to a source of fresh air preferably from outside the building. A second fitting 31 incorporating a pet-cock valve is attached to fitting 29 and provides a means whereby oxygen, or other gas or medicament may be introduced into the atmosphere inside the unit for special purposes. The air or gas being admitted through the fitting 29 passes through a box 32 which contains material for filtering the incoming air or gas. This sealed box 32 is preferably provided with means such as wing nuts 33 to allow rapid removal of the lid for changing the filter unit. The air or gas supplied through filter 32 is introduced into the system by connecting pipe 34 leading into the intake tube 28.

An enclosed type electrical heater 35 is mounted inside the intake tube 28 so that all of the circulated air may be heated prior to circulation by the blower fan 27. The heater 35 is provided with automatic controls which will be described later.

The blower fan 27 forces the air through outlet tube 36 through a valve unit 37. The control handle 38 projects outside the front of the base unit. Valve 37 is arranged to permit the air from the blower 27 to be directed either through the tube 39 or through the humidifier chamber 40. The valve 37, while it need not be considered here in detail, is so constructed that any proportion of the air being circulated may be directed through the humidifier chamber 40. Thus, accurate control of the humidification may be maintained since all of the air may be directed through the humidifying chamber or only that portion of the air required for adding a small amount of moisture when such a condition is desired. The humidifier chamber 40 has an external connection 41 which provides for filling the humidifier chamber from outside the base unit. Filler 41 also includes a sight gauge so that the amount of water in the humidifier is visible at all times. The humidifier chamber preferably incorporates a special sponge unit over which the air stream may be passed, thus providing for a large evaporation surface to give effective humidification without the need for ap-

plication of heat to the humidifier unit. This sponge arrangement also assures equivalent capacity for humidifying action even when the water level is low. After passing through the humidifier unit 40 or the by-pass tube 39 the air passes out through delivery box 42 which is located in one corner of the base unit 11 directly underneath the openings 43 in the floor plate 14. Openings 43 are clearly indicated in Fig. 1. A circular hole or opening 39a in the upper surface of by-pass 39 permits the air passing through the by-pass to enter the delivery box or duct 42.

The circulated gas is thus forced into the occupant's space by the blower through the grille openings 43 and removed from the occupant's space through the grille 44 at the opposite end of the incubator. The return air is drawn into the base unit where it is recirculated by means of the intake 28 to the blower. In order to provide for evacuation of a quantity of gas equal to the volume of fresh air added to the circulated air through the intake 29, a small opening 45 is provided in the enclosure unit 10. In the present arrangement this opening 45 is located in the access door 46.

The details of the access door are more clearly illustrated in Fig. 6 where it will be seen that the door 46 is provided with a hinge 46a and a latch 46b, thus permitting opening the access door for insertion and removal of various articles. Access door 46 is located near the bottom end of the mattress and is sufficiently large that articles to be used for feeding and caring for the occupant may be easily inserted and placed upon the floor 14 in the space provided between angle 20 and the enclosure. From this position the attendant may reach the articles through the portholes 47 in which the sleeves 48 are mounted.

The portholes and sleeves are illustrated more clearly in Fig. 7, where it will be observed that the long, flexible sleeves 48 are provided with an elastic ring 49 which causes each sleeve 48 to fit snugly around the attendant's wrist thereby preventing the air from the room from entering the occupant's space. In this fashion only the sterilized hands of the attendant come in contact with the air inside the enclosure. The use of flexible protective sleeves of this general nature is not in itself new. However, it will be noted that the portholes 47 are provided with an outwardly projecting rim in which a groove 50 is provided. An elastic ring 51 holds the end of the sleeve 48 in position in the groove 50, thus providing for quick but positive attachment or detachment of the sleeve 48. Sleeves 48 are preferably made from a transparent, lightweight, flexible, plastic material. This sleeve construction and method of attachment permit replacement to be easily made in case of damage. Also fresh sleeves may be provided at the time the incubator unit is cleaned or sterilized after each occupant's use in preparation for the next patient. It will be noted that sleeve 48 when not being used by the attendant may be easily folded as indicated at 48a to act as a seal to close opening 47. In some cases it may be desirable to add another pair of openings 47 with sleeves in the opposite wall of enclosure 10 as indicated in dotted outline. The present incubator construction lends itself readily to the adding of such access openings which are particularly useful under circumstances where one person holds the infant while another performs such an operation as intravenous feeding.

With the circulating system which has been

described a positive air pressure is produced at all times in the occupant's space due to the fact that the pressure side of the blower is connected by means of closed channels directly to the openings 43 to the occupant's chamber. This is of considerable advantage since any leakage from the enclosure is from the inside to the outside thus preventing room air which may be contaminated from entering the occupant's space. This arrangement also permits opening the access door 46 without danger of room air entering occupant's space since the flow during this brief period of opening will be from the inside of the dome unit 10 to the outside. In order to provide an indication that a positive pressure is being maintained at all times an indicator device is mounted at the opening 45 in the access door. Here a small, flexible diaphragm 52 is supported with one end covering the hole 53 in door 46 and the other end being retained by the rim of the opening 45. Passage of air outwardly through opening 53 causes a continual vibration or flutter of the diaphragm 52 which is readily noticeable by an observer. Should the pressure inside the dome be lower than the room air the diaphragm 52 moves to close the opening 53 and is stationary. Diaphragm 52 is preferably made of a flexible, bright-colored, plastic sheet arranged to be easily visible. This diaphragm thus forms a simple, reliable means of indicating that a supply of fresh air is being added to the circulation system. There is one operation which may produce a momentary suction action within the enclosure. This occurs during withdrawal of the sleeves if an attendant removes his hands rapidly. The resultant reduction in pressure causes the flutter valve 52 to be drawn against opening 53, thus closing it to prevent room air from being drawn in. As a result the suction causes a temporary increase in the amount of fresh air drawn into the system.

When room temperature conditions are such that cooling of the air in the occupant's space is desirable this is accomplished by the use of an ice chamber. The ice chamber 54 consists of a metal box mounted inside the base box 11 and preferably raised above the floor of the base box in order to permit the circulation of air over all surfaces of the ice unit, thus providing a maximum of radiation surface. The ice chamber 54 is provided with a lid 55 which may be attached in a fashion to completely seal the ice chamber from air leakage. It will be noted that below the return air opening 44 a small channel or duct 56 (see Fig. 4) is provided to conduct the air downwardly to below the upper surface of the ice chamber. In this way the return air is delivered from the occupant's space to the base unit chamber at a point where it will circulate in all directions over the ice box including the top and the bottom, in finding its way back to the blower intake 28. Effective cooling is thus provided.

The ice chamber may be loaded with ice cubes through the ice chute 57 which is located at the front of the base unit 11. Ice chute 57 is provided with a hinged lid 58. A drain pet-cock 59 permits draining off the water formed during the melting of the ice. The capacity of the ice chamber is sufficient to provide several hours cooling with one loading for room temperature of 100 to 105 degrees F.

In the return air duct 56 there is located a thermostat unit 60 which controls the operation of the air heater 35. Thermostat 60 may be adjusted to control the temperature of the circu-

lated air at different temperatures which may be selected by the external control knob 61. This arrangement provides for initial use of high temperatures, for example, 98 degrees for a new patient and the gradual reduction of the incubator's air temperature over a period of time until the patient becomes acclimated to normal room temperatures. The heater control remains effective even during actual operation when the ice chamber is in use. This prevents the possibility of cooling below the desired temperature. Electrical connections 62 include a connection from the thermostat 60 with the electrical equipment chamber 21 where it is connected into the line to control the operation of the heater 35.

Additional safety devices are provided for the operation of the incubator temperature and circulation equipment. The forced circulation of the air in the system is maintained at all times regardless as to whether the air is being heated. In order to indicate proper operation of the blower an indicator light 63 shows that the blower is running. This is in addition to the flutter valve 52 which indicates that proper replenishing of the air supply is being provided by the blower. A second indicator light 64, preferably amber in color, is provided to show when the heat unit is in operation. This light 64 is connected into the circuit of the heater 35 so that upon operation of the switch to cause operation of the heater 35, the indicator 64 is lighted.

A third safety indicator is provided to show when the temperature of the air in the system reaches a dangerous point. This might occur in case of faulty operation of the heater or upon an excessive temperature in the room in which the incubator is located. Direct sunlight upon the incubator unit might also cause increase in the inside temperature. The safety is arranged to operate when the incubator temperature reaches a predetermined amount, for example, 102° F. This causes the operation of red light 65 to show and at the same time sets off a buzzer to attract the attendant's attention. In addition, a relay is operated to open the heater circuit in case malfunctioning of this system may be the cause of the high temperature. Control of the safety device may preferably be by the use of a thermometer having contact wires located at the alarm temperature so that the mercury causes completion of the circuit when it reaches this point. Such a contact thermometer is indicated at 65a in the return air outlet 56 (see Figure 3). Wire connections 65b provide the means for completing the circuit to light 65.

Conductor wire outlets 66 are shown at the side of the electrical compartment 21 with wires leading to the various indicator lights 63, 64 and 65 and to control devices 60 and 65a.

A thermometer 67 is mounted inside the top of the hood 10 to permit the attendant to check the inside temperature at any time and thus determine the accuracy of the thermostatic control. It is also desirable to provide an opening 68 through which a rubber stopper 68a having a glass tube 69 may be inserted for purposes of providing a connection for special uses such as intravenous feeding or transfusions. When not in use the glass tube 69 may be provided with a closure or the stopper 68a may be replaced with a solid stopper to prevent escape of air from the enclosure. This access opening also permits stethoscopic examination and the like.

From the foregoing description it will be seen that I have provided an incubator construction

of greatly improved form. The compact base unit permits the unit to be readily assembled during production in a step by step fashion, thus reducing the cost of manufacture and providing for improved installation of the electrical and other equipment. The locating of all such equipment within a single metal enclosed box produces a compact unit which may be easily transported from one room to another, or even taken to a home in case of emergency. The arrangement of the circulating system with the inlet and outlet locations properly selected in the floor of the occupant's chamber provides for an effective circulation system in which an even temperature distribution may be effected. The use of a completely transparent dome for the occupant's compartment allows unrestricted vision from all directions and the arrangement for providing opening of the enclosure along the bottom edge permits such opening without excessive loss of interior conditioned air. This is further enhanced by the use of positive pressure in the opening which retards the ingress of air from the room in which the incubator is used. The provision of a removable floor for the occupant's space allows complete access to the base compartment for inspection, cleaning or servicing. This inspection and servicing of the various units is also extended to the individual units in the base which have lids which may be removed for access to their interior. Normal servicing of the humidifier and the cooling chamber are provided for from outside the incubator unit. The control and indicating system permits complete conditioning of the air or gas being circulated and provides the attendant with information as to the proper functioning of the apparatus at a glance. Accurate operation of the controls is assured by locating the control elements in the air stream directly as it leaves the enclosure space.

Throughout the specification and claims the terms air and gas have been used indiscriminately to indicate the circulated medium. Since the circulating and conditioning apparatus is equally capable of handling any desired mixture of gases, including particles of suspended vapor or solids which may be added for medical reasons, it is intended that these terms be construed in a broad sense to include any medium which may be circulated in the incubator.

I claim:

1. An incubator for infants having a shallow box unit enclosing apparatus suitable for circulating, heating and humidifying air, an isolating enclosure supported on top of said box unit, said box unit having an inlet opening in its upper surface for passing air into said enclosure, an outlet opening in its upper surface for withdrawing air from said enclosure, an opening for supplying air from an outside source to said circulating apparatus, said circulating apparatus being capable of providing a positive pressure in said enclosure, said enclosure having a small outlet opening to permit the escape of air and air-flow indicator means supported near said enclosure outlet opening.

2. An incubator having a base unit for enclosing air circulating, heating and humidifying apparatus, said base unit having an upper surface forming the floor of the enclosed occupant's space, a box-like enclosure composed of wall and upper surfaces, said enclosure being arranged to fit on said base unit, inlet and outlet openings in the upper surface of said base unit to

provide for circulation of air from said unit through said enclosure, intake means in said unit for supplying air from an outside source to said circulating apparatus, and air exhaust means in one of the surfaces of said enclosure.

3. For an incubator, an occupant's enclosure, a blower for circulating air through said enclosure in a fashion to produce a positive pressure therein with respect to the air outside said enclosure, an inlet structure for supplying air to said circulating blower, said enclosure having an outlet opening to permit air to pass therethrough, and an airflow indicator supported near said outlet opening.

4. Incubator apparatus suitable for infants having an enclosed base unit containing gas circulating, heating and humidifying equipment, a compartment inside said base unit and sealed therefrom, said compartment containing an electric motor and other electrical apparatus and having removable means to provide access to said compartment.

5. Incubator apparatus suitable for infants having an enclosed base unit containing equipment for circulating, heating and humidifying gas including a blower-fan, a humidifier unit through which gas from the blower-fan may be passed before reaching the occupant's space, by-pass means and valve means whereby any proportion of gas flowing from said blower-fan may be passed through said humidifier unit.

6. Incubator apparatus suitable for infants having a unit for housing circulating and conditioning equipment, said unit incorporating a blower device for circulating the gas, an enclosed duct running from the pressure side of said device to an opening into the occupant's chamber, a return air opening between the occupant's chamber and the base unit arranged to permit the return air to flow through at least a portion of said base unit to said blower device, intake opening structure for said blower device including an inlet from said base unit, and an inlet from outside said base unit whereby fresh outside air may be supplied to the air circulated by said blower device, an enclosed heating unit located in said intake structure in a position to heat both the recirculated air and the fresh air drawn from outside.

7. An incubator construction for infants having an occupant's chamber, bed means including a low wall structure to locate a mattress, a mattress tray having a flanged end and being adapted to lie inside said retaining wall or to be supported with said flanged end on said retaining wall to provide for either a flat or an inclined position of the mattress.

8. Incubator apparatus for infants including a separate unit containing circulating and heating equipment, an enclosed occupant's chamber, a surface structure between said unit and said chamber having an inlet opening between said

5

unit and said chamber for directing air into said chamber, an outlet opening for withdrawing air from said chamber, an electrical heating device associated with said circulating equipment, a thermostat for controlling said device located at the outlet opening in the path of the circulated air stream.

9. An incubator unit for infants having an occupant's chamber, said chamber having an opening to allow insertion of an attendant's arm, an external flange around said opening having an annular groove therein, a sleeve of thin flexible material having one end arranged to fit over said flange, a resilient ring adapted to fit in said annular groove and retain the end of said sleeve in intimate engagement therewith.

10. Infant incubator apparatus having an isolation compartment and a machinery compartment in communication therewith, a blower in the machinery compartment to circulate a current of air through both compartments in series, a power unit for said blower, and a housing for said power unit constructed to isolate the atmosphere about said power unit from the current of air passing through said compartments.

11. Infant incubator apparatus comprising a base unit enclosing air conditioning and circulating apparatus, a removable occupant's enclosure unit fitted on said base unit, yieldable material sealing the juncture between said units, a fresh air intake to said base unit and filter means in said intake; a stale air exhaust from said enclosure unit, having a uniflow valve to prevent ingress of air.

12. Infant incubator apparatus having an enclosed occupant's compartment and a separate base unit containing equipment for the circulation, humidification and heating of gas, including a blower fan, a humidifier unit through which gas from the blower fan may be passed immediately before reaching the occupant's space, a bypass duct and a control valve to permit the proportioning of the amount of gas flowing through said humidifier unit and a heater device inserted in the system at a point to warm the gas before it reaches the humidifier unit.
